JAMES ARNOLD, OF PAWTUCKET, RHODE ISLAND.

Letters Patent No. 103,277, dated May 24, 1870.

IMPROVEMENT IN STOPPING MECHANISM FOR DOUBLING, SPOOLING, AND LIKE MACHINES.

The Schedule referred to in these Letters Patent and making part of the same.

To all whom it may concern:

Be it known that I, JAMES ARNOLD, of Pawtucket, in the county of Providence and State of Rhode Island, have invented a new and useful Improved Stop-motion for Spoolers; and I do hereby declare that the following specification, taken in connection with the drawings making a part of the same, is a full, clear, and exact description thereof.

This invention is applicable to machines used for doubling several yarns into one, commonly called spooling-machines. In such machines two or more yarns are led from as many bobbins, and combined in one thread, which is wound upon a spool, a revolving motion being given to the spool which gives the necessary draft to unwind the several yarns from their bobbins. With such machines, stop-motions have heretofore been employed, so that, upon the breaking of any one of the yarns, the motion of the spool upon which it should be wound is arrested.

For this purpose various devices have been contrived, most of which make use of weighted levers supported by the yarns, any one of which levers in changing position in consequence of the breaking of its supporting yarn will stop the further rotation of the spool. Sometimes these levers are made to act to stop the spindle which revolves the spool. In other instances they act to hold the spool without stopping the spindle; and, in a third instance, they cause the spool to be stopped by disconnecting it from the source of its motion.

My improvement consists in the employment of devices which act to gradually stop the spool by seizing and holding fast the three or more yarns which are being doubled, at some point between the place where the breakage occurs and the spool, and thus prevent a broken end from losing itself on the spool.

In the drawings—

Figure 1 is a side view of so much of a spooler as will enable the improvement to be understood.

Figure 2 is a front view, showing a section of the supporting-standard and tripping-wires.

Several yarns, *a a a*, are led from as many different cops or bobbins, which bobbins are conveniently arranged on a creel or frame.

Each yarn supports, in an upright position, a separate weighted wire lever, *A*, pivoted to the supporting standard *B* at *b*. If the yarn breaks, the lever will fall to the point indicated by dotted lines.

C is a spring catch, which may be of any preferred construction. In this instance it is a flat spring, secured to the standard *B* at *c*, with the short arms *d* of the several wire levers *A* so located with respect to the same that, when any one of such levers is in the position indicated by dotted lines, the upper

end of the spring *C* will be forced outward from the standard.

The upper end of the spring is furnished with a catch, *e*, with which the foot-piece *f*, on the rod *D*, can be engaged, as will presently be described.

The several strands of yarn are collected into one thread, which is led through an eye, shown in section, at *E*. From the eye it passes between the two disk-plates *F F'* over the roller *F²* to the spool.

These plates perform the function of spring pressure-fingers in closing upon the thread, and holding it fast so soon as one of the single strands composing it, by reason of breaking, allows one of the wire levers to fall. This mode of operation is accomplished by the following means.

The rod *D*, which carries the two plates *F F'*, is fitted to slide in bearings *G G*. A stop-pin, *g*, limits the extent of its downward movement, and in this instance the bent end of the foot-piece *f*, locking with the bent neck of the spring catch *e*, limits its range of upward movement.

The upper plate *F* is free to turn around the rod *D*, but is otherwise fixed in position, while the lower plate *F'* is not only free to turn around the rod, but is capable of being moved along the rod for a distance equal to the space between the under surface of the fixed upper plate *F* and a collar or shoulder, *h*, on the rod *D*.

H is a coiled spring, wound around the rod *D*, the lower end of which rests upon the bracket *G*, and the upper end against a stock-pin, *i*. The upper extremity of the rod *D* is furnished with a button-head, *I*, for conveniently working the rod.

When the machine is in operation, the rod *D* is held by the spring catch *e* in the position shown at fig. 1.

The two plates *F F'* are thus separated by a distance which allows the free passage of the thread to the spool, which spool is placed upon a spindle and held by a slight friction with a resisting power less than the tensile strength of the thread winding upon the spool.

So soon as one of the yarns composing the thread breaks and allows the lever which it previously sustained to fall, the catch *e* will be tripped, and the spring *H* will fly upward, causing the pin *g*, or other mechanical device employed for the purpose, to bring the upper surface of the plates *F F'* into close contact with the under surface of the plate *F*; consequently the several strands composing the thread, including the one with the broken end, will be held fast, and such broken end be prevented from running onto the spool, and the spool itself be stopped by the superior strength of the yarns composing it, over the friction

which drives the spool. By this means, the advantages above mentioned are secured, and the attendant is able to piece the broken end with the greatest facility and expedition.

As has been before stated, the plates F F¹ are arranged to turn on the rod D. This arrangement is of special advantage, for the reason that it allows the said plates to turn for a quarter of a circle after they have closed upon the thread, and thus bring the spool to a stand-still with less suddenness than if the plates stopped the spool upon the instant that their surfaces came together.

If it is desirable to do so, a yielding spring can be combined with such plates, and the axle upon which they are placed, to still further prevent the injurious consequences of a sudden strain.

In the drawings, the spring finger-plates are shown in a horizontal position, and this is the most convenient way to arrange them, in my opinion; but it is quite easy to place them perpendicularly without departing from the principle of the invention.

I wish it to be understood that I do not claim the

application of a tripping mechanism or stop-motion to a spooler. Neither, on the other hand, is the invention confined to the particular construction and arrangement of the tripping mechanism in its combination with the spring finger-plates F F¹, but includes those formal variations of construction which come within the capacities of competent workmen.

What I claim as my invention, and desire to secure by Letters Patent, is—

1. The pressure-finger F F¹, for seizing the double thread upon the breaking of a single strand, when such fingers are free to turn on or around the rod or axle on which they are mounted, and thereby gradually check the rotation of the spool, substantially as herein described.

2. The combination of pressure-fingers F F¹, constructed as above described, with a suitable tripping mechanism or stop-motion, substantially as specified.

JAMES ARNOLD.
